JULES JEANNOTAT, OF PATERSON, NEW JERSEY.

Letters Patent No. 61,665, dated January 29, 1867.

IMPROVEMENT IN APPARATUS FOR CLEANING SILK THREADS.

The Schedule referred to in these Letters Patent and making part of the same.

TO ALL WHOM IT MAY CONCERN:

Be it known that I, JULES JEANNOTAT, of Paterson, in the county of Passaic, and State of New Jersey, have invented a new and improved "Silk Cleaner;" and I do hereby declare that the following is a full, clear, and exact description thereof, which will enable others skilled in the art to make and use the same, reference being had to the accompanying drawings, forming part of this specification.

The object of my invention is to produce a simple device for freeing silk from knots, clearing it of extra growth and all foreign substances that may have adhered to it, and it consists in the employment or use of two plates secured in a suitable shaped frame or stand in such manner that their proximity to each other, or nearness of their edges, may be regulated in a simple manner, to accommodate different sizes of silk. This invention also consists in combining with the above a guide or fender, as will be hereinafter described. In the accompanying drawings—

Figure 1 is a front elevation of my invention; and

Figure 2, a plan or top view of the same.

Similar letters of reference indicate like parts.

A represents the frame or stand, which, in the present instance, consists of two arms projecting upward from a fixed base, which latter is to be made fast to the frame or rail of the machine with which it is to be used. B B are two steel plates of about the same size. These plates are set in grooves or recesses made in the face of the arms of the stand to receive them, and are held in place by a set-screw, a, in each plate near the middle of their length. The inner edges of these plates, or those toward each other, are made perfectly square, so that they will fit accurately if placed together; and the inner top corners are filed rounding, so as to permit the silk to be easily dropped in between them. The bottoms of the plates have their inner corners filed off, and the stand has also a triangular piece cut out, which, together, make a diamond-shaped hole, as shown clearly in fig. 1, at b. By inserting the end of any suitable shaped tool, as a screw-driver, in this diamond-shaped hole, and twisting it in a proper manner, the plates can be spread apart evenly or equidistant from each other throughout their entire length; and this is an important feature, as it enables the plates to be set so as to adapt the device to different sizes of silks, and in such manner that the work will be performed accurately and in a superior manner. I design tempering the plates sufficiently hard to prevent their edges wearing by use. By using this device for cleaning silk, a greater amount of work, in my opinion, can be done than by any other cleaner now in use, and the silk will be cleaned in a superior manner; it makes less waste, and is less troublesome to the operator, for the reason that the plates can be adjusted quickly and without the use of a wrench, and it requires no packing, and is withal a simple device, not likely to get out of order. C, in the drawings, represents the guide or fender for the silk-cleaner. This guide consists of two pieces, D, of wire, each bent into a similar shape, as shown in the drawings, and fitted at one end into the top of the stand A, extending in opposite directions. These wires should be sufficiently long to extend from one cleaner to another, when a series of them are used upon a common frame, so as to connect all together upon one and the same side of such frame, the wires being inclined toward each other, so as to cause the silk to run down the same, and, passing through the opening E, between their lower ends, then pass to and between the cleaner-plates. Among the many advantages of the guide C, in connection with my improved silk-cleaner, may be here mentioned that it prevents the silk from running on either side of the cleaners, however careless or inattentive the operator may be; that the guide is simple and neat, and not clumsy in appearance or use.

What I claim as new, and desire to secure by Letters Patent, is—

1. The plates B B, secured to and adjustable in the stand A, in the manner and for the purposes described.
2. The combination of the plates B B, stand A, and set-screws a, substantially as herein shown and described.
3. The combination, with the silk-cleaner herein described, of the guide or fender C, substantially as and for the purpose specified.

JULES JEANNOTAT.
